CHARLES WHITING BAKER, OF MONTCLAIR, NEW JERSEY.

METHOD OF AND APPARATUS FOR FEEDING LIQUID FUEL TO INTERNAL-COMBUSTION ENGINES.

1,149,322.

Specification of Letters Patent.

Patented Aug. 10, 1915.

Application filed July 31, 1913. Serial No. 732,158.

To all whom it may concern:

Be it known that I, CHARLES WHITING BAKER, a citizen of the United States, residing at Montclair, in the county of Essex and State of New Jersey, have invented certain new and useful Improvements in Methods of and Apparatus for Feeding Liquid Fuel to Internal-Combustion Engines, of which the following is a specification.

10 It is the object of my invention to substitute for the ordinary carbureter, commonly employed on internal combustion engines, an apparatus which will deliver the fuel into the inlet air passage in finely atomized form, and in proper quantity for all variations of speed and load, the quantity of fuel delivered being directly controlled by the operator or by an automatic governor, whereas in the ordinary carbureter, the liquid fuel is drawn in by the suction of the entering air and can only be controlled by the operator indirectly, by means of the throttle-valve on the air inlet pipe to the engine.

15 In my improved method of feeding liquid fuel, a small rotary pump, driven by the engine, draws the liquid fuel from a reservoir and forces it in a fine stream into contact with a stream of air or gas moving at high velocity, through a contracted passage.

20 The liquid fuel is atomized by the rapidly moving air current, and is carried forward mingled with it as a fine fog into the inlet air pipe of the engine, where it mixes with the entering air. I provide means, as hereinafter described, for closely regulating the quantity of oil delivered by the rotary pump according to the speed of the engine and the load upon it. While the quantity of 25 the air or gas used for atomizing will also vary according to the speed of the engine and the amount of liquid to be atomized, close regulation is not necessary here, as my experiments have shewn that with a 30 high velocity of the air current, only a moderate quantity of air is needed to atomize even the largest quantity of fuel that the engine can use. The volume of atomizing air should be sufficient, however, to give a 35 high velocity through the contracted passage in which the stream of oil comes in contact with the current of air, without making the contracted passage so small that it is liable to accidental stoppage. I prefer also 40 to use a low pressure for the atomizing air,

one to ten pounds per square inch, as higher pressures are not necessary to give the required velocity for fine atomizing.

My invention will be understood by reference to the accompanying drawings in which—

Figure 1 is a side elevation of an automobile engine equipped with my improved means for fuel feeding; Fig. 2 is a longitudinal section of the atomizer; Fig. 3 is a partial sectional elevation of a modification showing a means for utilizing exhaust gases from the engine for producing the atomizing blast; and Fig. 4 is a sectional detail of the oil feed pump.

Similar reference numerals indicate similar parts in the several views.

The engine shown in Fig. 1 comprises two cylinders 1 and 2, suitably incased, and having inlet chambers 3 and 4 respectively, connected to a common manifold or header 5 with intake tube 6. 7 designates the crank case in which is journaled the driving shaft 8 and lay shaft 9 operating the valve mechanism in the usual manner.

A rotary fuel pump 10 is attached to any convenient rotating part of the engine. As shown in Fig. 1, the pump is driven from the lay shaft 9 through the speed-reducing gearing 11 and shaft 12, the latter being connected to the pump through a variable speed friction drive, comprising a driving wheel 13 slidably mounted on shaft 12, and a disk 14 fast on the shaft 15 of the pump. The purpose of the variable speed friction drive is to vary the amount of fuel fed to the engine according to the load upon it, and it operates in the well-known manner, the driving wheel propelling the driven disk 14 at variable speed according as the driving wheel is near the center or near the periphery of the disk. This form of drive is fully illustrated and described in my application Serial No. 776,214, filed June 28, 1913. The position of the driving wheel is under the control of the operator through a lever 14' which may be interlocked with, and move with, the throttle-lever 15 through the medium of a rod 16 connected to the throttle-lever on the steering wheel. By this means the rate of feed of the fuel is directly governed. This fuel pump may be driven by suitable means from any other rotating part of the engine. Any suitable pump may be employed for this purpose. That shown in

22
 Fig. 4 comprises two similar gears 16 and 17 intermeshing with each other and mounted for rotation in a tight fitting case 18. The oil is admitted to the case through an inlet 19 and is carried by the gear teeth to an outlet 20, the gears being rotated in the directions indicated by the arrows, by a gear on the shaft 15. The liquid fuel is thus delivered to the engine in a continuous stream 10 in the quantity required by the engine. To give a general idea of the proportion of the parts, if an automobile engine requires one one-hundredth cubic inch of gasoline per revolution at full load, and if the speed-reducing gear is such that the pump, when the friction gear is set for highest speed, runs at one-tenth the speed of the engine, then the pump should deliver one-tenth cubic inch per revolution. At lighter loads, 20 the pump will deliver the same quantity per revolution but its speed in proportion to the engine will be reduced by the friction gearing so that the quantity delivered per engine revolution will be less.

25 The pump 10 draws its supply of fuel from a reservoir and can do this even if the reservoir is at a lower elevation than the engine, as may happen on an automobile or motor boat, so that no air pressure system 30 for the reservoir is required.

It is one of the most important practical advantages of my invention that kerosene, or other fuel oils cheaper than gasoline, may be used as a fuel when once the engine is 35 heated, gasoline being used for starting only. To do this I provide two reservoirs, one for gasoline and the other for the second fuel, having delivery pipes 21 and 21' respectively, which are connected by a 40 three-way cock 22 to the suction pipe 19 of the oil pump. By a lever under control of the operator, the cock 22 may be moved, connecting the pump suction to either reservoir, or, if desired, to draw from both and 45 so produce a mixture of the two fuels in any desired proportions. The liquid fuel is delivered from the pump through pipe 20 to an atomizer 23.

In order to prevent any possibility of 50 leakage of the liquid fuel from the reservoir through the pump 10 into the atomizer 23 when the pump is idle, I prefer to place in the discharge pipe a small check valve 24 kept closed by a spring 25, as shown in detail in Fig. 2. When the pump is running, it delivers the fuel under pressure sufficient 55 to lift valve 24 and force the fuel past it, but the valve is automatically closed the instant the pump stops.

60 The atomizer, shown in longitudinal section in Fig. 2, consists of a contracted throat in the delivery pipe 26 through which the atomizing agent flows whereby said atomizing agent is caused to pass through this 65 smaller passageway at high velocity. The

liquid fuel is discharged by the pump through a pipe which terminates in this contracted throat, and the oil as fast as it flows is atomized by contact with the moving air current. The air carrying the atomized oil 70 as a fine mist is discharged through the outlet 27 into the center of the intake 6. A suitable baffle 35 may be placed above the outlet 27 to facilitate the mixing of the fuel charged atomizing air jet with the more 75 slowly moving current of air drawn in by the engine.

A convenient construction for the atomizer as shown in Fig. 2, is to make it in the form of a T-coupling into the lower end of 80 which is connected the casing for valve 24 and spring 25, and into the arms of which are connected the pipe 26 leading from the supply of atomizing agent, and outlet 27 extending into intake 6, said outlet having a 85 contracted orifice as shown.

The air or gas under the necessary pressure for atomizing the oil may be obtained in several ways with apparatus of such 90 small size and simplicity as to make it commercially feasible. For example, as shown in Fig. 1, a small rotary pressure-blower 28 may be employed driven directly by the engine through shaft 9 and gearing 11. Such a blower requires no valves, and will 95 deliver a continuous stream of air at sufficient pressure to effect the atomizing of the oil fuel, the air being delivered through pipe 26 to the atomizer.

In an engine operating on the two-stroke cycle, the air under pressure to effect the atomizing may be taken from the scavenging air reservoir or the crank case. I prefer, however, especially where kerosene is to be 100 used as fuel, to use hot exhaust gas from the engine for atomizing the oil. For this purpose, as shown in Fig. 3, a small hole is drilled into one or more of the engine cylinders, and a pipe 29 extending through the water space and leading to a reservoir 30 105 is inserted. The hole is so located in the barrel of the engine cylinder 2, that it will be uncovered by the piston a short time before the exhaust valve opens, and the burned gas under pressure will thus escape through the pipe 29 into the reservoir 30 during this time. This will occur at every working stroke. In starting the engine, before explosions begin, the air or gas compressed 110 by the piston on the compression stroke will be forced through the pipe 29 until its opening is covered by the piston. To prevent any backward flow from the reservoir 30 into the cylinder of the engine, a light check valve 31 is placed in the exit pipe 29. The 115 purpose of the reservoir 30 is to change the intermittent flow from the cylinder 2 into a continuous flow through the atomizer 23 and thence to the engine. A screen 32 is 120 placed in the reservoir 30 between the inlet 125 and the exit pipe 29.

and the outlet to catch any particles of soot or other solid matter so that they may not clog the atomizing passage. One end of the reservoir is removable for access to the interior, and a relief-valve 33 may be placed upon it to prevent over-pressure in case explosions should occur inside the reservoir.

In the apparatus shown in Fig. 3, I employ the same form of atomizer shown in Figs. 1 and 2, the hot gas from the reservoir being discharged through the contracted passage of the atomizer by a pipe 34 leading from the reservoir 30, and the stream of oil from the pump 10 is delivered through the pipe 20 and check valve 24 into the moving current of hot gas. This stream of hot gas not only breaks up, by its mechanical action, the stream of liquid fuel into a fine fog, but by its high temperature, it vaporizes a part of the liquid fuel and thus carries it into the inlet air passage in the best possible condition for thorough mixture with the entering air and for complete combustion. It will be apparent that the pipe through which the mingled current of hot gas and atomized fuel is discharged into the inlet air pipe may be placed in any desired position, vertical, inclined or horizontal, and the inlet air pipe of the engine consequently may be placed in any position which the designer may find convenient.

While I have shown and described the above method of and apparatus for engine fuel feeding as applied to an automobile engine, it is applicable to any type of engine using liquid fuels, such as may be atomized by the apparatus above described.

It will be understood, of course, that where the conditions require it, the variation in the rate of fuel feeding by the variable speed friction drive to correspond to variations in load may be made automatically by a governor mechanism instead of being made by the operator.

45 What I claim is:—

1. The method of feeding liquid fuel to an internal combustion engine which consists in delivering a continuous stream of such fuel to the engine proportioned in quantity to suit the engine's speed and the load upon it, and subjecting said stream of liquid fuel to the atomizing action of a current of high pressure fluid in such manner that the rate of flow of said continuous fuel stream will not be affected by the action of said atomizing current, and delivering said atomized fuel with the atomizing fluid to the intake pipe of the engine.

2. The method of feeding liquid fuel to an internal combustion engine which consists in delivering a continuous stream of such fuel to the engine proportioned in quantity to suit the engine's speed and the load upon it, and subjecting said stream of liquid fuel to the atomizing action of a current of gas

under pressure flowing from the engine cylinder in such manner that the rate of flow of said continuous fuel stream will not be affected by the action of said atomizing current, and delivering said atomized fuel with the atomizing fluid to the intake pipe of the engine.

3. In an internal combustion engine, the combination with means for delivering a continuous stream of liquid fuel to the engine proportioned in quantity to suit the engine's speed and the load upon it, of means for atomizing the fuel by the action of a current of high pressure gaseous fluid, said atomizing fluid being so applied as not to affect the rate of flow of the liquid fuel, and means for delivering said fluid with the atomized fuel into the air intake pipe of the engine.

4. In an internal combustion engine having a throttle valve to control its speed and power, the combination with means for measuring and delivering a continuous stream of liquid fuel to the air intake pipe of said engine in quantity proportioned to the speed and power of the engine, of means for atomizing said stream of fuel by the action of a current of high pressure gaseous fluid without interfering with the rate of flow of said fuel and said fluid, and means for delivering said fluid and atomized fuel into the air intake pipe of the engine below said throttle valve.

5. In an internal combustion engine, the combination with means for delivering a continuous stream of liquid fuel to the engine, of means for regulating the quantity of said fuel according to the speed of the engine and the load upon it, means for atomizing the fuel by the action of a current of high pressure gaseous fluid, and means for delivering said fluid with the atomized fuel into the air intake pipe of the engine without affecting the rate of flow of said fuel.

6. In an internal combustion engine using liquid fuel, and controlled by a throttle valve, a liquid fuel atomizer discharging into the intake pipe of said engine below the throttle valve, means for delivering to said atomizer a continuous stream of liquid fuel proportioned to the engine's speed and load, and means for delivering a current of gaseous fluid at high velocity to said atomizer.

7. In an internal combustion engine, having an air intake, the combination of a liquid fuel atomizer discharging into said intake, means for delivering a continuous stream of liquid fuel to said atomizer, means for regulating the quantity of said fuel according to the speed of the engine and the load upon it, and means for delivering a current of gaseous fluid at high velocity to said atomizer.

8. In an internal combustion engine using

liquid fuel, the combination with a pump driven by the engine delivering a continuous stream of liquid fuel in quantity suited to the engine's speed and load, of means 5 for atomizing said liquid fuel in its passage to the engine, said means comprising a pipe through which a current of gaseous fluid is caused to flow at high velocity and in which the stream of liquid fuel meets said current, 10 the pipe delivering into the air intake of the engine.

9. In an internal combustion engine controlled by a throttle valve and using liquid fuel, the combination of a fuel oil pump 15 driven by the engine and delivering a continuous stream of fuel, a variable speed gear for varying the ratio of pump speed to engine speed according to the load upon the engine, and means for atomizing said stream 20 of fuel by a current of gaseous fluid moving at high speed through a pipe into which the liquid fuel is delivered, said pipe dis-

charging into the air inlet of the engine below said throttle valve.

10. In an internal combustion engine controlled by a throttle valve, the combination with means for measuring and delivering a continuous stream of liquid fuel to said engine in quantity proportioned to the volume of air passing through said throttle valve, 25 means for atomizing said stream of fuel without varying its rate of flow by a jet of gas from the engine cylinder, and means for delivering the atomized fuel and gas 30 into the air intake pipe below the throttle 35 valve.

In testimony whereof I have hereunto signed my name in the presence of two subscribing witnesses.

CHARLES WHITING BAKER.
